AIR-HEATING FURNACE WITH BAFFLED
ANNULAR AIR-HEATING PASSAGEWAY

Domenico A. Marro, Rutland, Vt.

Application August 24, 1950, Serial No. 181,186

2 Claims. (Cl. 126—99)

1

This invention relates to new and useful improvements in furnaces and the primary object of the present invention is to provide a furnace having a heating chamber and an air passage about the heating chamber through which a cool stream of air is directed to be heated by the hot walls of the chamber and then directed to outlet conduits leading to one or more room areas.

Another very important object of the present invention is to provide a heating unit of the aforementioned character wherein the air entering the passage will have a maximum travel to prolong the period of air in the passage so that the air will have sufficient time to be heated by the hot walls of the burner chamber.

A further object of the present invention is to provide a heating unit including a novel and improved arrangement of staggered baffles to reduce the speed at which air is passing through the passage and which baffles also reinforce and strengthen the entire unit which is constructed of sheet metal parts welded together.

A still further aim of the present invention is to provide a hot and cold air furnace that is simple and practical in construction, strong and reliable in use, efficient and durable in operation, inexpensive to manufacture, and otherwise well adapted for the purposes for which the same is intended.

Figure 1 is a front elevational view of the present invention;

Figure 2 is a reduced horizontal sectional view taken substantially on the plane of section line 2—2 of Figure 1;

Figure 3 is a reduced horizontal sectional view taken substantially on the plane of section line 3—3 of Figure 1;

Figure 4 is a vertical sectional view taken substantially on the plane of section line 4—4 of Figure 1;

Figure 5 is a horizontal sectional view taken substantially on the plane of section line 5—5 of Figure 1;

Figure 6 is a side elevational view of the invention with the outer cylindrical wall removed and with parts of the unit broken away; and,

Figure 7 is an enlarged fragmentary view of Figure 1 and with parts broken away and shown in section.

Referring now to the drawings in detail, wherein for the purpose of illustration, there is disclosed a preferred embodiment of the present invention, the numeral 10 represents a hollow body including a cylindrical wall 12, an upper

2

horizontal wall or plate 14 and a lower horizontal wall or plate 16. The plate 12 is provided with a depending flanged portion 18 that enters the upper end of the wall 12 and the plate 16 is provided with an upstanding flanged portion 20 that enters the lower end of the wall 12. The flanged portions 18 and 20 are secured to the wall 12 by fasteners 22.

An inner cylindrical wall or sleeve 24 is mounted in the body 10 concentric of the wall 12. The upper and lower ends of the sleeve 24 are secured to and in sealing contact with the plates 14 and 16 by welding or the like to form a combustion chamber C.

10 A plurality of supporting legs 26 having in-turned feet 28 at their lower ends support the body 10 in an elevated position. The inturned flanges 30 at the upper ends of the legs 26 are secured to the lower plate 16 by bolts or the like 32.

15 A discharge tube 34 extends radially through the forward portions of the walls 12 and 24 and is fixed by welding or the like to the walls 12 and 24. The inturned flange 36 at the forward end of the tube 34 is removably secured to the mounting flange 38 of an oil burning device 40 (of any suitable well known type) by bolts 42 and the delivery end 44 of the device 40 extends axially through the tube 34 for heating air in the chamber C.

20 Opposing openings in the lower and rear portions of the walls 12 and 24 receive an outlet neck or conduit 46 that is welded to the inner wall 24. The conduit 46 supports an external ring 48 that is secured to wall 12 by fasteners 50 or by welding and the conduit 46 is coupled with a flue 51.

25 A hollow cylindrical member 52 is supported on the upper plate 14. The bottom of the member 52 is open and the member 52 includes a peripheral flange 54 at its open bottom that is removably secured to the plate 14 by fasteners 56. The upper wall of the member 52 is formed with a plurality of apertures or openings in which the inlet ends of supply conduits 58 are suitably fixed. The conduits 58 extend to room areas that are to be heated.

30 First and second sets of vertically disposed baffles 60 and 62 are mounted within the air passage P provided between the walls 12 and 24. The baffles 60 depend from the upper plate 14 and terminate above the bottom plate 16 and the baffles 62 rise from the plate 16 and terminate below the plate 14. The baffles 60 alternate with the baffles 62 so that the air travelling in

the passage will climb up one baffle and then climb down the next baffle.

An air supply pipe 64 extends through an aperture A in the forward portion of wall 12 to enter the passage P adjacent and below the device 40. The upper plate 14 is formed with an opening 66 that communicates with the passage P adjacent the device 40. A vertical partition 68 within the passage P. The opening 66 is located on one side of the partition 68 and the pipe 64 is located on the other side of the partition but close to the opening 66 to permit maximum travel of air directed through the passage by air impelled into the passage through the pipe 64.

In practical use of the present invention, the fuel is burned in the chamber C and effects a heating of the wall 24. Air is directed through the pipe 64 and into and through the passage P in contact with the hot wall 24. The air in passage P moves relatively slow due to the baffle arrangement assuring that the air in the passage will be heated sufficiently when it enters the room areas by way of opening 66, member 52 and conduits 53.

Having thus described the invention, what is claimed as new is:

1. A furnace comprising inner and outer concentric walls having an air passage therebetween, a bottom plate closing the lower ends of both walls, an upper plate closing the upper ends of both walls, a hollow member supported upon the upper plate, a plurality of outlet pipes extending from the member, said upper plate having a single opening forming a communication between the interior of said member and said passage, a burner supported exteriorly of said outer wall and including a discharge end extending radially through both walls and terminating within the confines of the inner wall, an outlet conduit extending radially through both walls and having an inlet end within the confines of the inner wall, baffle means within the passage, and an air inlet pipe having an outlet end entering the passage and a vertical partition between said walls, said partition being located between said pipe and said

opening whereby air entering the passage by way of the pipe will be directed about the passage before rising in the opening.

2. A furnace comprising inner and outer concentric walls having an air passage therebetween, a bottom plate closing the lower ends of both walls, an upper plate closing the upper ends of both walls, a hollow member supported upon the upper plate, a plurality of outlet pipes extending from the member, said upper plate having a single opening forming a communication between the interior of said member and said passage, a burner supported on said outer wall and including a discharge end extending radially through both walls and terminating within the confines of the inner wall, an outlet conduit extending radially through both walls and having an inlet end within the confines of the inner wall, baffle means within the passage, an air inlet pipe having an outlet end entering the passage, said baffle means including first and second sets of vertical baffles, the baffles of said first set alternating with the baffles of said second set, the first set of baffles rising from the bottom plate and terminating below the upper plate and the second set of baffles depending from the upper plate and terminating above the lower plate, and a vertical partition in the passage extending between the upper and lower plates, said single opening being disposed on one side of the partition and said outlet end of said air inlet pipe being disposed on the other side of the partition, whereby the air to be heated will flow through the sinuous pathway defined by the baffles from the air inlet pipe to the opening.

DOMENICO A. MARRO.
